United States Patent Office

Des. 181,922
Patented Jan. 21, 1958

181,922

EDUCATIONAL PROTRACTOR

Pearl M. Bush, Canastota, N. Y.

Application February 15, 1956, Serial No. 40,175

Term of patent 14 years

(Cl. D52—1)

Fig. 2.

Fig. 1.

Figure 1 is a front view of an educational protractor embodying my new design; and

Figure 2 is an edge view of the educational protractor shown in Figure 1.

I claim:

The ornamental design for an educational protractor, as shown.
